UNITED STATES PATENT OFFICE.

JOHN M. MARTY, OF CLEVELAND, OHIO.

INJECTOR.

SPECIFICATION forming part of Letters Patent No. 341,029, dated May 4, 1886.

Application filed August 18, 1885. Serial No. 174,701. (Model.)

To all whom it may concern:

Be it known that I, JOHN M. MARTY, a citizen of the United States of America, residing at Cleveland, in the county of Cuyahoga and 5 State of Ohio, have invented certain new and useful Improvements in Injectors, of which the following is a specification, reference being had therein to the accompanying drawings.

My invention has relation to steam injectors 10 and ejectors, as more fully hereinafter described and set forth.

In the accompanying drawings, Figure 1 is a longitudinal sectional view of my injector. Fig. 2 is an elevation of the combining-tube. 15 Fig. 3 is an elevation of one end of my invention.

The object of my invention is to form an adjustable lifting injector and ejector with a single row of tubes, and not regulated by any 20 changes of the steam-supply, but by different positions of the mixer and discharge tubes. I accomplish this result by combining the mixer and discharge tubes, and prolonging the discharge-tube sufficiently to project beyond the 25 shell 1. To the rear end of this combining-tube 2, I attach a handle, 3, said handle having arms 4 extending forward, having on their ends beveled lips 5, made so as to work in the grooves of the large threaded neck 6 on the rear end of 30 the injector, to enable the operator to adjust the said tube 2 to any position required by the working of the machine, and to enable him to tell by the position of the said handle just how the machine is feeding.

35 The combining-tube 2 is provided with suitable perforations, 7 8 9, for the overflow and discharge. I also provide for a stuffing-box, 10, which screws on the threaded neck 11 at the end of the large threaded part 6, said stuffing-box having a flange, which extends nearly to the arms 4, and prevents the combining-tube 2 from slipping completely out without first unscrewing the stuffing-box 10. Into the front 40 end of said tube 2 is secured a mixer-tube or 45 nipple, 12, which has a perforation, 13, corresponding to the perforation 7 in the combined tube.

Inside of the steam-pipe connection 14 is secured the force-tube 15, which extends far 50 enough into the water-pipe 16 to allow the combining-tube 2 to fit closely over its small end and form an injector. The shell or body

of the injector has in its upper face three perforations, 16 17 18, said perforations being stopped by screw-plugs, thus rendering access 55 to the inside of the injector easy, and facilitating the cleaning of the same, the threads in said openings being pipe-size threads, to allow of pipes being connected to that side, if necessary. The central perforation, 18, is for 60 the purpose of an overflow-valve having a loose disk, 19, covering the bottom opening, and having an upright piece, 20, attached to its upper face, said piece working in an opening, 21, in the bottom of the plug, and preventing the disk from ascending too far or turning over.

In order to draw or lift water I pull the combining-tube 2 backward by turning the handle 3, causing the lips 5 on the arms 4 to 70 follow the grooves of the large threaded neck 6, thus enabling the steam issuing from the steam-tube 15 to pass off through the overflow without having to go through the mixer-tube. When the water appears at the overflow I 75 screw the combining-tube 2 forward toward the steam-tube 5 until the water stops coming out of the overflow. Thus I can at will form an ejector or an injector, and regulate the supply of water according to the given pressure 80 or the amount of steam required. It will be seen that the perforations 7 enable the water and steam to pass off through these perforations (one being on either side of the tube 2 and opposite each other) while you push the 85 tube forward, and the perforations 8 are within the solid shell 1, between the perforations 17 and 18. These perforations 7 also render the injector automatic, because, under a small pressure only, they start themselves when interrupted (breaking) as the steam blows out of these holes until the water in 16 gets sufficient body to condense the steam-jet again.

If the injector gets hot from any cause, I can take out the combining-tube 2, give steam, and 95 draw water any reasonable height. The water thus lifted and thrown out rapidly cools the shell or body 1.

To facilitate the inspecting and cleaning of the machine I arrange for perforations in the 100 casing opposite the pipe-connections for the passage of the steam and water while the combining-tube is pushed forward.

Having described my invention, what I claim

as new, and desire to secure by Letters Patent, is—

1. In an ejector and injector, as above described, the shell or body 1, having perforations 16 17 18, having screw-plugs stopping the same, overflow-valve having disk 19, pin 20, screw-plug having indentation 21, steam-tube 15, secured on the inside of the steam-connection 14, large threaded end 6, substantially as 10 shown and described.

2. In an ejector and injector, as above described, combining-tube 2, having handle 3, having arms 4, beveled lips 5, perforations 7 8 9, mixer-tube 12, secured within said combining-tube, stuffing-box 11, substantially as 15 shown and described.

3. The combining-tube 2, the mixer-tube 12, and discharge-tube projecting through the shell 1, which are reciprocated at the will of 20 the operator so as to draw or lift water and to regulate the supply.

4. In an ejector and injector, as above described, the combining-tube 2, having mixer-

tube 12, perforations 7, 8, and 9, the closed end of said tube projecting through the shell 25 1, and adapted to being moved back and forth by means of the handle 3, arms 4, and beveled lips 5, working on the threaded neck 6, or equivalent means.

5. In an ejector and injector, as above described, the combination of the shell or body 1, having perforations 16 17 18, and screw-plugs stopping the same, steam-tube 15, secured on the inside, steam-connection 14, large threaded neck 6, and stuffing-box 10, secured 35 on the small threaded neck 11, with combining-tube 2, having perforations 7 8 9, mixer-tube 12, screwing inside of said tube, substantially as shown and described, and for the purposes set forth.

In testimony whereof I affix my signature in presence of two witnesses.

JOHN M. MARTY.
